EDGAR COCKS, OF LOS ANGELES, CALIFORNIA.

FOLDING BED.

Application filed December 3, 1925. Serial No. 72,870.

This invention relates generally to bed structures, and particularly to folding beds, of the portable type, adapted to be concealed, when not in use, within a closet or recess and moved therefrom into a room for use. These are ordinarily termed "recess beds" and the desiderata are compactness and mobility.

The dominant features of beds of this type comprise a base, portably supported upon rollers, and a bed frame pivotally mounted thereon to swing in a vertical plane, being disposed vertically for storage or horizontally for use. When disposed horizontally the frame overhangs the base.

In order to occupy a minimum of storage space and be movable through standard width doors, the base is made as small and compact as possible, consistent with its functional requirements; and to facilitate in lowering and raising the bed frame, balance springs are provided between the frame and base. These are of sufficient strength to normally hold the frame in its vertically disposed position, but weak enough to be overcome by its unbalanced weight when disposed horizontally for use. The frame is pivotally supported adjacent one end and when a mattress and bedding are placed thereon its unbalanced weight is considerable, therefore, the balance springs must possess considerable tensile strength to minimize the physical effort required to raise or lower the frame and bedding between the horizontal and vertical positions. As the tensile strength of the balance springs is greatest when the bed frame is in its horizontal position, and as this tension is increasing as it is being moved to this position from the vertical, their tendency is to tip the base in the same direction the frame is being moved and this is augmented by the shifting of the center of gravity of the entire structure relative to the base. To overcome this tendency either a great deal of undesirable weight must be added to the base or it must be made of a plan area so large that it cannot be conveniently stored in comparatively small recesses or easily passed through standard width doors.

With these problems in mind, my improvement is directed to certain features of the base, my object being to provide a simple and compact structure, including one or more flexible, auxiliary supporting legs, which may be moved to folded position, when the frame is vertically disposed for storage, or

moves to extended position when the frame is lowered to the horizontal for use.

By this means I am enabled to utilize a base of minimum plan area, and to effectively increase this area when necessary to counteract 60 tension of the balance springs, obviating possibility of the base collapsing on the frame when it is moved for use, but without sacrificing any of the desired compactness for storage or weakening the tensile strength of the 65 balance springs to the point of requiring excessive physical effort in raising or lowering the bed frame.

Another feature of my improvement is the provision of means to prevent movement of 70 the bed frame from the vertical to the horizontal until the foldable auxiliary leg is moved to its extended position; thereby preventing possibility of an oversight and resultant injury to the operator. I also provide 75 a suitable latching arrangement to prevent accidental movement of the auxiliary leg from its extended position, such as might be done by its catching on the edge of rugs when the bed is moved.

The invention herein shown and described is similar to my invention shown and described in a copending application filed Dec. 3, 1925, Serial No. 72,869; the invention of this application differing from the former 85 in specific details relating to the operation of the auxiliary leg and the means of preventing movement of the bed frame while the auxiliary bed is in folded position.

In the following specification I describe 90 the details of construction, arrangement and operation of my improvement, reference being made therein to the accompanying drawings, wherein I have illustrated its preferred specific embodiment. I wish it to be understood, however, that this particular embodiment is shown and described merely for the purpose of fully disclosing the general principles of my invention and that I reserve the right to make such changes and modifications 95 in structure as will properly come within the scope of the invention as defined by the claims appended hereto.

In the drawings:

Fig. 1 is a fragmentary front elevation of 105 my bed structure, illustrating the bed frame in its vertically disposed position on the base and the auxiliary leg in its folded position;

Fig. 2 is a sectional plan view taken as indicated by the line 2—2 of Fig. 1; 110

Fig. 3 is an enlarged, fragmentary, detailed plan view, taken as indicated by the line 3—3 of Fig. 1, showing the auxiliary leg in folded position;

Fig. 4 is a detailed view similar to Fig. 3 illustrating the auxiliary leg in extended position;

Fig. 5 is a fragmentary, detailed view taken as indicated by the line 5—5 of Fig. 3;

Fig. 6 is a fragmentary, detailed view taken as indicated by the line 6—6 of Fig. 4; and

Fig. 7 is a small, diagrammatic side elevation illustrating movement of the bed frame.

Referring first to Figs. 1 and 2 the numeral 10 designates generally a base, movably supported upon a plurality of rollers 11. This base is composed of arcuate end members 12, a rear transverse brace member 13 and a front, transverse brace member 14. The end members 12 are made arcuate to facilitate in movement of the base into and out of small recesses, such as closets and through doors of substantially standard width. The rollers 11 may be rigid or of the caster type.

Standards 15 are rigidly supported upon the base 10, adjacent the forward ends of the end members 12 and uprights 16 and are mounted upon the rear ends of these members, which are suitably jointed to form the head of the bed. A bed frame 17, carrying suitable springs 18, is pivotally mounted upon the standards 15 through the medium of pivot pins 19 carried by the latter. As illustrated in Fig. 1 the pivotal connections between the standards 15 and frame 17 are adjacent the head end of the frame, so that the head end overhang is substantially equal to the height of the standards 15 above the base 10. Brace members 20 may be provided between the standards 15 and uprights 16 to lend rigidity to the structure.

A plurality of contractile, helical springs 21 are each connected at one end to a transversely disposed brace member 22, carried by the side frame members 17^a and at their opposite ends to the transverse brace member 14 of the base 10. These springs I have termed "balance springs" for the reason that they are provided to normally hold the bed frame 17 in its vertically disposed position, as illustrated in Fig. 1, and to minimize the physical effort required to raise and lower this frame, upon the base 10, between its vertical and horizontal positions, as diagrammatically illustrated in Fig. 7. Any number of springs 21 may be provided to give the desired cushioning effect and the tensile strength is arranged in accordance with the size of the bed, the weight of the frame 17, with its springs 18, and the usual amount of bedding.

An auxiliary leg 23, preferably formed of converging arms 24 and 25, is pivotally mounted upon the base 10, the arm 25 being

joined to a plate 26 by means of a pivot pin 27, and the arm 24 likewise joined to a plate 28 by means of a pivot pin 29. Plate 26 is carried by a transverse brace member 30, supported between standards 15, and plate 28 is carried by the transverse brace member 14. Pins 27 and 29 are necessarily coaxial and their common axis tilted slightly from the vertical, as illustrated in Fig. 1, to raise the swinging end of the auxiliary leg free of the floor when in folded position and to bring it into engagement with the floor when in its fully extending position. If desired a suitable roller or caster wheel 31 may be provided on the outer end of the leg 23. To form a rigid structure a brace rod 32 joins the divergent ends of the arms 24 and 25.

A contractile, helical spring 33 is secured at one end to an angle plate 34, on the transverse brace member 14 and at its opposite end to the arm 24, of leg 23, adjacent to and forward of its pivot 29. This spring is disposed (see Figs. 2, 3 and 4) to swing over the pivotal axis of the leg 23, to either hold it in folded position, as illustrated in Figs. 1, 2 and 3, or extended position as illustrated in Fig. 4. Its strength is only sufficient to assist in swinging the auxiliary leg 23 and to lightly hold in either folded or extended position so as not to interfere in any way with its manual movement.

An arcuate arm 35 is mounted upon and carried by the arm 24, of leg 23, concentric with the axis of pivot pin 29, being rigidly braced as by means of a member 36. Upon movement of the leg 23, from the position illustrated in Fig. 3 to that shown in Fig. 4, and vice versa, the arm 35 will travel in a circle as shown.

A pin 37 is carried by a plate 38 secured to the head end frame member 17^a and is so arranged that when the bed frame 17 is in its vertically disposed position, as illustrated in dotted lines in Fig. 7, it will extend at right angles to the plane of movement of the arcuate arm 35. This is more clearly illustrated in Fig. 5. It is also positioned to be encircled by the arm 35 when the leg 23 is in its folded position, as illustrated in Figs. 2 and 3. By this means the bed frame 17 cannot be tilted downwardly, as illustrated diagrammatically in Fig. 7, until the auxiliary leg 23 is moved from the folded position illustrated in Fig. 3, to its extended position as illustrated in Fig. 4; the length of arm 35 being such that the pin 37 cannot pass its end 39 until the leg 23 has reached its fully extended position as illustrated in Fig. 4. The end 39, of arm 35, may, if desired, be pointed or rounded so that it may be engaged by the pin 37 and moved to its fully extended position upon downward movement of the frame 17.

A pair of links 40 and 41, pivotally joined together at 42, are each pivotally mounted upon the base member 14 and arm 24 by

means of pivot pins 43 and 44, respectively. Pin 43 connects one end of link 40 with a bracket 45 and pin 44 connects link 41 with a bracket 46 through the medium of arm 50. Brackets 45 and 46 are likewise pivotally mounted upon the members 14 and 24 by means of pivot pins 47 and 48, respectively. Link 41 has a flattened portion 49 extending beyond its pivotal point 44, to serve as a toe plate for the purpose hereinafter stated.

Links 40 and 41 are of such length that their inner pivotally connected ends will drop slightly below a line passing through the centers of pivot pins 44 and 45 when the arm 23 is in its fully extended position, as illustrated in Fig. 6. Engagement of the link 40 with the transverse brace member 14 limits this downward movement. By thus dropping past center the links 40 and 41 serve as a latch and prevent accidental movement of the leg 23 from its fully extended position towards its folded position.

When arranged for storage in a closet or recess the frame 17 is normally disposed vertically, with reference to the base 10, as illustrated in Figs. 1 and 7, being yieldingly retained in this position by the contractile action of springs 21. When so arranged the bed may be conveniently rolled in or out of the recess and through doors of standard width. For this reason the base 10 is made as narrow as possible, in the direction of depth, and may be of sufficient length to accommodate a bed frame of standard width or length. Thus the base 10 is substantially oblong in configuration, as illustrated in Fig. 2.

When in the position just described the auxiliary leg 23 is in the position illustrated in Figs. 1, 2 and 3, being yieldingly retained in this folded position by the contractile action of spring 33. When in this position the arcuate or semi-circular arm 35 passes around and embraces the pin 37, as shown in Fig. 3, thereby preventing any downward movement of the frame 17.

When it is desired to lower the frame for use, from vertical to horizontal position, as illustrated diagrammatically in Fig. 7, the auxiliary leg 23 is first manually moved from the position illustrated in Figs. 1, 2 and 3 to that illustrated in Figs. 4 and 7. If the leg has been extended to its fullest extent the end 39 will clear the path of travel of the pin 37, upon downward movement of the frame 17, and the links 40 and 41 dropped from the position illustrated in Fig. 5 to that illustrated in Fig. 6. While the spring 33 tends to swing the leg 23 to its fully extended position the links 40 and 41 limit this movement and upon dropping to the position illustrated in Fig. 6 latch it against accidental movement.

After the leg 23 has been fully extended the frame 17 may then be lowered, as illustrated in Fig. 7.

While the combination of the pin 37 and arcuate arm 35 has been provided to obviate possibility of an oversight in failing to properly extend the leg 23 before swinging the frame 17 to the horizontal position, there will 70 obviously be no danger of the frame 17 being returned to its full vertical position before the leg 23 is folded. After the frame 17 has been returned to the vertical position it is only necessary to step on the toe plate 49, 75 thereby throwing the links 40 and 41 from the position illustrated in Fig. 6 to that illustrated in Fig. 5, and this aided by the contractile action of spring 33, will move the leg 23 to its folded position as illustrated in 80 Figs. 1, 2 and 3.

By referring to Fig. 7 it can be readily seen that the contractile action of springs 21 tends to always keep the base 10 and frame 17 in the relative positions illustrated by the 85 dotted lines. Consequently when the frame 17 is lowered from the vertical towards the horizontal position the tendency of these springs is to cause the base 10 to tip in the direction indicated by the arrow "A", which 90 is very easily accomplished by these springs, especially if they are of sufficient strength to be of any assistance in raising or lowering the frame 17 with the usual amount of bedding thereon and also if the base 10 is sufficiently 95 narrow, in the direction of depth, as to render it capable of being easily passed through the usual width door opening and into a comparatively small recess. By providing the auxiliary leg 23 the plan area of the base may 100 be readily increased to a depth sufficient to offset the contractile effect of springs 21 in tipping the base. It may also be readily seen that in moving the frame 17 from the vertical to the horizontal that the center of 105 gravity of the entire bed structure will shift from substantially the line "B" to line "C" and that this will augment the tendency of springs 21 to tip the base 10. In fact this unbalanced weight of the frame alone will 110 tip the base if it is made too narrow and not properly weighted.

From the foregoing disclosure it is apparent that with my improvement the base may be made very light and narrow thereby 115 effecting a saving in cost of manufacture and transportation as well as minimizing space required for its storage when not in use.

Having described a preferred form of my invention, I claim:

1. A portable folding bed, comprising a base, a bed frame pivotally mounted on the base to swing vertically thereon and overhang the base when in horizontal position, an auxiliary leg pivotally mounted on the base 125 to swing horizontally from folded position longitudinally of the base to extended position transversely of the base, an arm rigid with said leg, and a pin on the frame, said pin and arm being so positioned that when the 130

frame is in vertical position the pin will be embraced by the arm to prevent movement of the frame towards the horizontal until after the leg has been moved to extended position.

2. A portable folding bed, comprising a base, a bed frame pivotally mounted on the base to swing vertically thereon and overhang the base when in horizontal position, an auxiliary leg pivotally mounted on the base to swing horizontally from folded position longitudinally of the base to extended position transversely of the base, a toggle like connection between the auxiliary leg and base to hold the leg in extended position, and means carried by and movable with the leg adapted to engage a member of the frame when the parts are in folded position to prevent movement of the frame from vertical position.

3. A portable folding bed, comprising a base, a bed frame pivotally mounted on the base to swing vertically thereon and overhang the base when in horizontal position, an auxiliary leg pivotally mounted on the base to swing horizontally from folded position longitudinally of the base to extended position transversely of the base, a spring connecting said leg and the base and acting to either hold the leg in folded position or to swing it outward from the base, a curved arm connected with the leg and extending rearward of the forward edge of the base, and a pin connected with the bed frame and adapted to be positioned in front of said curved arm when the frame is in upright vertical position, substantially as and for the purpose described.

4. A portable folding bed, comprising a base, a frame pivotally mounted on the base

to swing vertically thereon and overhang the base when in horizontal position, an auxiliary leg pivotally mounted on the base to swing horizontally from folded position longitudinally of the base to extended position transversely of the base, a spring connecting the leg and base and acting to hold the leg in folded position, a locking mechanism comprising brackets pivotally connected to the base and auxiliary leg, two links respectively pivoted to said brackets and to each other, the forward of said links being extended to provide a foot rest, the parts being so arranged that when the leg is fully extended, said links will prevent movement of the leg to folded position until bodily moved by pressure on said foot rest, for the purpose described.

5. A portable folding bed, comprising a base, a bed frame pivotally mounted on the base to swing vertically thereon and to overhang the base when in horizontal position, an auxiliary leg pivotally mounted on the base to swing horizontally from folded position longitudinally of the base to extended position transversely of the base and beneath the overhanging portion of the bed frame, hook means carried by and movable with the leg and complementary means carried by the frame adapted to be embraced by the hook means, said hook means being arranged to embrace the complementary means to prevent movement of the frame from its vertical position until the leg has been moved to its extended position.

In witness that I claim the foregoing I have hereunto subscribed my name this 30 day of October, 1925.

EDGAR COCKS.
